UNITED STATES PATENT OFFICE.

LOUIS BOUCHER, OF WEST SUPERIOR, WISCONSIN, ASSIGNOR OF ONE-HALF
TO ARISTIDE PATRIE, OF SAME PLACE.

DRAG FOR STEERING VESSELS.

SPECIFICATION forming part of Letters Patent No. 508,271, dated November 7, 1893.

Application filed May 11, 1893. Serial No. 473,814. (No model.)

To all whom it may concern:

Be it known that I, LOUIS BOUCHER, of West Superior, in the county of Douglas and State of Wisconsin, have invented a new and 5 useful Improvement in Steering Apparatus, of which the following is a specification.

This invention relates to an improved steering apparatus, and is designed to be used only when a ship's rudder becomes disabled, thus 10 affording safety to ocean travel, and preventing serious mishaps.

As the device is only used when the rudder or steering apparatus becomes disabled, I construct my apparatus in such a manner, 15 that it may be stowed away in the vessel when not in use, and when needed can be set up in a very short time.

With these objects in view my invention consists of a drag, a chain connected therewith, and a capstan upon which the ends of the chain are wound to move the drag to one side or the other.

My invention consists also in certain details of construction and combination of parts all 20 of which will be fully described.

The drawing hereto annexed shows the rear portion of a vessel equipped with my improved steering apparatus.

In carrying out my invention I employ an 25 air tight cylindrical drag A, of metal or other suitable material, and at the ends and center of this cylinder are secured the annular flanges or fins a for the purpose of increasing the friction of the drag and rendering its 30 action more positive and rapid. The forward end of the drag is pointed, and connected therewith is a ring a' to which is attached a chain B. This chain B, is connected at the forward end to the center of a second chain

35 C, the ends of which second chain, are passed around the pulleys D, mounted in the outer ends of the beams E, E, which project obliquely forward from each side the vessel near its rear end. The ends of the chain C after 40 being passed around the pulleys D are connected, each to a separate single pulley block F, at each side of the vessel and movable back and forth. At each side of the vessel is also 45 secured a double pulley block G, and to each 50 single block F is connected a third chain H, said chain being passed through one pulley

of the opposite double block G, thence back through the single block and thence back again through the second pulley of the double block. The chain is then connected to the 55 capstan I, which is journaled longitudinally between the beams E E, and is provided with an ordinary wheel K. It will thus be seen that each single block is connected with the opposite double block and then with the capstan, and it will also be noticed that each 60 double block is fixed, while the single blocks are movable; and that the chains as they pass from the double blocks are wound around the capstan in opposite directions. By this construction and arrangement there is an equality of tension attained, and as one single block is drawn inward the other is allowed to 65 move outward, and as the chain C, is connected with these blocks it will be so drawn 70 around the stern of the vessel that its center will be moved to one side or the other of the center of the boat, and the chain B, which carries the drag A being secured to the center of this chain C, the drag will be moved to one 75 side or the other and in this way draw more upon one side of the ship than the other and pull the ship in that direction.

In operation, when the ship's rudder becomes disabled, the beams are brought out 80 and set in place, the capstan erected and the chain and blocks connected therewith. The chain C is then connected, the drag A attached and dropped overboard. All the parts being in their proper positions, the drag will 85 swing directly to the rear of the stern, but should the starboard chain be drawn tight the port chain will be loosened, and the drag will be drawn to starboard and pull the ship in that direction. 90

While I have shown and described the chain B and the extra chain H and blocks they may be dispensed with if desired, and the chain C, connected directly to the capstan and have the drag connected directly to the 95 chain C. The chain B, is preferred, however, as it makes the device more positive and the blocks and chains are used to avoid sudden jerks in moving from one side to the other.

Having thus described my invention, what 100 I claim as new, and desire to secure by Letters Patent, is—

1. The combination of a vessel, the beams secured thereto carrying pulleys at their outer ends, the capstan, the fixed and movable pulley blocks and ropes connecting them with the capstan, the drag chain connected with the movable blocks, and the drag attached to said chain, said drag consisting of a cylindrical body provided with annular flanges or fins, substantially as shown and described.
- 5 2. In a steering apparatus a drag composed of a hollow cylinder having annular flanges or fins at its ends and center, a tapered end

and a ring in said end substantially as shown and described.

3. In a steering apparatus, the combination of a cylindrical drag A having fins a, the chains B, and C, the beams D, and pulleys E, movable blocks F, the ropes H, and the capstan to which said ropes are connected, substantially as shown and described.

15 LOUIS BOUCHER.
